DESIGN FOR A COMBINATION SERVING COUNTER AND ENTERTAINMENT STAGE UNIT

Egbert G. Smith, Buffalo, N. Y.

Application January 27, 1942, Serial No. 105,453

Term of patent 7 years

To all whom it may concern:

Be it known that I, Egbert G. Smith, a citizen of the United States, residing at Buffalo, in the county of Erie and State of New York, have invented a new, original, and ornamental Design for a Combination Serving Counter and Entertainment Stage Unit, of which the following is a specification, reference being had to the accompanying drawing, forming part thereof.

Fig. 1 is a perspective view of a combination serving counter and entertainment stage unit showing my new design.

Fig. 2 is an enlarged plan view of the same, the drapery and associated embellishment being omitted.

I claim:

The ornamental design for a combination serving counter and entertainment stage unit, as shown.

EGBERT G. SMITH.
